UNITED STATES PATENT OFFICE.

JOSEPH ZUBATY, OF FLINT, MICHIGAN, ASSIGNOR TO A C SPARK PLUG COMPANY, OF FLINT, MICHIGAN, A COMPANY OF MICHIGAN.

SPEEDOMETER.

Application filed February 1, 1928. Serial No 251,172.

My invention relates to an improvement in the construction of speedometers of the type in which the speed is indicated by the rotation of a speed cup. The speed cup 5 usually has secured to it a hair spring which acts to provide the proper resistance against the rotation of the speed cup so that the latter will always indicate the correct speed, and also to return the speed cup to zero 10 position when the vehicle has stopped.

The object of my invention is to provide a simple device which is easily secured in place without the use of any separate fastening means, and which will serve as an 15 adjustable abutment for one end of the hair spring and also be as an adjustable stop to limit rotation of the speed cup in either direction.

Other objects and advantages will be apparent upon referring to the specification and accompanying drawing, in which:

Figure 1 is a fragmentary top view of a speedometer with the casing removed, showing my improved hair spring holder and 25 stop member in connection therewith.

Figure 2 is a front view of the speedometer with the face plate removed.

Figure 3 is a fragmentary side view of the construction shown in Figure 1.

30 Figure 4 is a detail view showing my combined hair spring holder and stop member in perspective.

The reference numeral 10 indicates the frame of a speedometer of the well known A C type, in which a speed cup 12 is caused to rotate by the magnetic action of a rotor which is rotated inside the speed cup in the usual manner. Fastened to the frame by screws 14 is a support 16 in which is journaled the upper end of the speed cup spindle 18. This support has formed in it slots 20. A stamped member 22, shown in Figure 4, has formed on it extensions 24 and arms 26 and 28. The arm 26 is bent back upon itself as at 28, and has formed on it a lip 30 in which is provided a hole 32, which extends through both thicknesses of the metal. This stamped member 22 is placed against the underside of the support 16, the extensions 24 fitting into slots 20, and the ends of the extensions 24 being bent as at 34 over the upper face of the support 16 to hold the stamped member 22 securely in place against the support. The arm 26 is bent as at 36 to clear the spindle 18. The

usual hair spring 38 is secured at its inner end to the speed cup 12, and its outer end passes through the opening 32 in the arm 26, and is held therein by means of a pin 40 which is driven into the opening 32. The 60 purpose of this hair spring is, of course, to furnish the proper increasing resistance against rotation of the speed cup 12 so that the latter will always indicate the correct speed, and also to cause the speed cup to 65 return to zero position when the vehicle has stopped. In order to compensate for manufacturing variations, it is desirable that the tension of the hair spring may be varied in order to properly calibrate the mechanism 70 when assembled. In my construction, this can be easily accomplished by bending the arm 26 in either direction, since being made of a stamping it has sufficient spring to permit this.

The speed cup 12 has struck up from its lugs 42 and 44 as shown in Figure 1. The lug 42 strikes against one side of an arm 28 when the speed cup is in its zero position. The lug 44 strikes against the opposite side 80 of the arm 28 should the speed cup be rotated to the other extreme, which would indicate the maximum mileage that the instrument is capable of indicating. This would serve to prevent damage to the instrument which would be apt to take place if the speed cup were permitted to be rotated past this position. In order to adjust the zero position of the speed cup so that the figure 0 will come exactly behind the stationary pointer on the face plate, the arm 28 85 may be bent in either direction. 90

It will be seen that I have thus provided one simple member which may be easily secured in place without the use of any screws, rivets or other separate fastening means, and which serves both as an adjustable abutment for the hair spring, and also as an adjustable stop for limiting the rotation of the speed cup. Either the hair spring holding arm 95 or the stop arm may be adjusted independently of the other. Obviously, this is a very inexpensive construction, and at the same time it is very satisfactory.

It is thought that from the foregoing 105 taken in connection with the accompanying drawing that the construction and operation of the device will be apparent to those skilled in the art, and that various changes in size, shape and proportion and details of con-

struction may be made without departing from the spirit and scope of the appended claims.

I claim:

- 5 1. Speed indicating mechanism comprising a frame, a support on said frame having a pair of slots therein, a stamped spring holding and speed cup movement limiting member provided with a pair of extensions, 10 said extensions fitting into said slots and being bent around said support to secure the stamped member to said support.
- 15 2. Indicating mechanism comprising a frame, a support on said frame having a pair of slots therein, a stamped member provided with a pair of extensions adapted to fit into said slots and to be bent around said support to secure said member to said support, a rotatable indicating member, and a 20 spring to return said indicating member to zero position, said stamped member serving as an abutment for one end of said spring and also as stop to limit the rotation of said indicating member in either direction.
- 25 3. Speed indicating mechanism comprising a frame, a support on said frame, a speed cup rotatably journalled in said support, a member secured to said support and having formed on it two arms, a hair spring 30 having one end secured to said speed cup and the opposite end secured to one of said arms, and lugs formed on said speed cup and cooperating with the other arm to limit the rotation of said speed cup in either direction.
- 35 4. Speed indicating mechanism comprising a frame, a support on said frame, a speed cup rotatably journalled in said support, a

stamped member secured to said support, an arm extending out from said member, and a hair spring secured at one end to the speed 40 cup and at the opposite end to said arm, the latter being adapted to be bent to vary the tension of said spring.

5. Speed indicating mechanism comprising a frame, a support on said frame, a speed cup rotatably journalled in said support, a stamped member secured to said support, an arm extending out from said member and lugs formed on said speed cup and cooperating with said arm to limit the rotation of said speed cup in either direction, 45 said arm being adapted to be bent to vary the zero position of said speed cup.

6. Indicating mechanism comprising a frame, a support on said frame having a pair 55 of slots therein, a stamped member provided with a pair of extensions, said extensions fitting into said slots and being bent around said support to secure said member to said support, a pair of arms formed on 60 said stamped member, a rotatable indicating member, a spring secured at one end to said indicating member and at the other end to one of said arms, the latter being adapted to be bent to vary the tension of said spring, 65 and lugs formed on said indicating member and cooperating with the other arm to limit the rotation of said indicating member in either direction, the last mentioned arm being adapted to be bent to vary the zero 70 position of said indicating member.

In testimony whereof I affix my signature.

JOSEPH ZUBATY.
